UNITED STATES PATENT OFFICE

ELIJAH E. NEAL, OF CORAL GABLES, MIAMI, FLORIDA, ASSIGNOR TO PEERLESS HAND-CUFF COMPANY, OF SPRINGFIELD, MASSACHUSETTS, A CORPORATION OF MASSACHUSETTS

HANDCUFF

Application filed June 21, 1927. Serial No. 200,466.

This invention relates to an improvement in handcuff, thumb cuff, leg cuff and like police cuff constructions and particularly in handcuffs of a particular type. For the prior art background I refer to my Patent No. 1,531,451 of March 31, 1925 which shows the particular type improved. My said earlier patent shows a type of handcuff construction which is now in extensive use in the police departments of this country and abroad. A short consideration of such use will help to give a complete understanding of the present invention.

Handcuffs are put in use intermittently at rare rather than frequent intervals. For the most part they are carried in the officer's pocket, forming part of his equipment, in the same way as a revolver. The total weight of an officer's equipment is considerable. As a matter of actual practice in the sale of handcuffs, the weight of the structure is given in ounces because the buyers always want to know the weight. They are also much concerned with the over-all dimensions of the handcuffs and the facility with which they can be carried in the pocket for instant availability when needed. As such a time if any part of the structure can catch on the pocket corners and delay the operation of getting them out and applied, the delay is serious. Such delay is quite apt to give the opportunity for an escape. The officer's hands need to be free from all possible structure that might cause him to bungle his job under the great variety of circumstances in which he needs to apply the handcuffs.

A characteristic of the handcuff type improved by this invention, is that it will not lock until it embraces the wrist, or something equivalent, which prevents further movement of the locking arm in that direction which would permit it to unlock if such movement were continued. According to one feature of this invention, the exterior form of that type of handcuff is changed. The purpose of this change in form is not alone to give a better appearance to the cuff, although such an effect is one of the general objects. A more specific object for purely utilitarian purposes is to so change the form

and construction of the particular type of handcuff as to render it lighter, simpler, and safer from the officer's viewpoint.

According to another feature of the invention, the number of parts in the completed handcuff is less than in my prior construction, which is an important advantage provided that the new construction will function as well or better than the old, which it will do. It is true that the new details of construction are related to the lock parts, but the purpose of the new details is related to the manufacture and more particularly to the use of the handcuff as a whole, whereby the handcuff as a complete structure has improved characteristics.

The other features of the invention will be apparent from the detailed description and claims. In the drawings

Fig. 1 is a plan view of a pair of handcuffs drawn to actual size so as to show the form and indicate the lack of excess weight of the completed structure when compared with prior art structures;

Fig. 2 is a detail view with one cheek plate of the lock casing removed and with the locking mechanism disclosed in position for operation;

Fig. 3 is a detail end view of the cuff looking at the lock casing from the left in the upper part of Fig. 1;

Fig. 4 is a side view of the latch for the lock;

Fig. 5 is a plan view of the bolt strip with the latch spring formed in the strip;

Fig. 6 is a side view of Fig. 5;

Figs. 7 and 8 are plan and end views of a suitable form of key for the lock; and

Fig. 9 is a detail view like Fig. 2 except that an additional means is shown adapted to prevent a certain type of lock picking operation.

By reference to the prior art, the Carney Patent No. 1,017,955, for example, the general arrangement of two spaced arms 1 and 2 having an intermediate arm 3 pivoted between one pair of ends at 4 and a lock casing formed between the sides of the arms 1 and 2 at the opposite ends is old. It is also old generally to have the intermediate arm 3

free to rotate completely about its pivot 4 so as to be locked by engagement of the mechanism in the lock casing with the teeth 5 on arm 3 only when a wrist or its equivalent is 5 embraced by the arms. This is brought about by the fact that the arm 3 is normally free to move by the lock casing in one direction only. Since these features are generally old, 10 no particular emphasis will be placed on such structural features and their advantages will be assumed, except where they are important with relation to the new features.

As shown in the drawings, the new structure provides a lock casing A of shallow trough-like form. The depth of this trough is preferably just about equal to the width of the locking arms between the lock casing and the pivot for the intermediate arm. The 20 bottom of this trough may be closed as shown by a skeleton closure piece B serving also to space the sides of the spaced arms 1 and 2 at the lock casing ends, and so that the general contour of the arms may follow smoothly into the contour of the lock casing. 25 Thus the lock casing A is formed as a crescent-shaped portion very closely allied to the curved form of the arms. The form as well as the greatly reduced size of my lock casing stands out in sharp contrast when compared with the heavy space-occupying box-like structures of lock casings shown in all the prior art structures of the Carney, Wesson, and my own prior patents, all of which 30 permit the characteristic operation of complete rotations of the locking arm past the lock casing until the embraced wrist is grasped by the cuff. Such box-like lock casings are the only ones that have been used with the handcuffs of this type in actual 40 police use, and so far as I am aware, are the only forms known for the purpose of enclosing satisfactory locking mechanism up to the time of the present invention.

Within the shallow trough of my crescent shaped lock casing I provide an efficient locking mechanism, preferably made of but two movable parts. A straight latch 15 is mounted so as to have its opposite ends engaged for a very slight see-saw movement about the 50 pivot 16 intermediate its ends. This pivot pin is fastened between the cheek pieces of the lock casing and preferably in line with pivot 4 and the pivot of eye 20 of the chain connecting the pair of cuffs. Instead of the 55 pivot pin, I may provide curved guides at the ends of the latch lever in the closure piece B which guides may have their curved surfaces respectively determined as arcs struck from the center where the pivot pin would otherwise be located. By such an arrangement the 60 necessity of the pivot pin may be avoided as the latch lever will tip or see-saw from the same center as if a pivot pin were used, but the form shown in the drawings is the one 65 preferred.

At one end of latch 15 I provide ratchet teeth to engage the ratchet teeth 5 on the outer curved edge of arm 3. As the arm 3 is moved past the lock casing, the toothed end of lever 15 must tip enough to let the arm 3 70 ratchet its way by the casing. This is a very small movement so that the trough of the lock casing on this side of the pivot 16 can be and is made of a shallow depth as shown, so as to accommodate only the necessary 75 movement. Near the other end of latch 15 a slot is provided, wide enough to permit a key to enter, turn therein and engage the adjacent end of the lever to tip it in the direction desirable for the latch teeth to avoid the teeth 5 on arm 3. The necessary tipping movement at the key engaged end is less than that at the other end of the lever because of the difference in the distances from the ends of the latch to the pivot 16. As a consequence, when the key operates to tip the latch 15 by bearing on the short arm, more force is necessary than is used to tip the lever from the end of the long arm. This arrangement is preferable because as the member 3 moves to 80 ratchet by the long arm of the latch, the movement should be easy, but when the lever 15 is tipped to unlock the member 3, the movement should be relatively hard so that it will require about all the force that can be applied by a key and be so made as to effectively resist the smaller force that can be applied by a lock picking wire.

The latch 15 has a spring, as will be later described, bearing against it near the end of its long arm which spring normally presses the lever to locking position for member 3. This spring and the key are the means for tipping the latch 15 from opposite ends through the very small "see-saw" action 100 which is the only necessary movement for said latch. When the ratchet teeth on the long arm of latch 15 are moved to unlocking position by tipping the latch on its pivot by the key, the short arm moves toward the path of the teeth on intermediate arm 3. To prevent any jamming action between the short arm and such teeth, the adjacent edge of the short arm is cut away from a point 105 near the pivot to the end of the short arm, as shown. This permits the whole of latch 15 to lie just as close to the edge of the intermediate arm as is possible without jamming. In fact the whole of latch 15 is arranged substantially tangent to the teeth of the intermediate arm 3, and the required tipping action of the latch 15 is a very small departure 110 from such tangent. The above described arrangement for latch 15 is in part what permits a small size shallow lock casing for 115 the handcuff.

It is quite desirable and almost a necessity from the policeman's standpoint, to double lock a handcuff of this type. Thus the latch 15 should be locked to arm 3, not only by a 120

spring engagement in the first instance, but by a bolted engagement after the handcuffs have been applied to a prisoner. This double locking feature broadly is shown in my 5 prior patent and its desirability in practice is one of the reasons why a rather costly and bulk producing contrivance has heretofore been considered necessary in these handcuffs. I show herein means to perform this 10 locking operation by quite different means than shown in my prior and other patents. My new means in this regard is particularly designed to simplify the structure of the cuff, to occupy a very small space, to add 15 almost nothing to the weight, and to co-operate with latch 15 not only to bolt the latter in locking position to give the double lock, but to serve such lever also in its single locking function.

20 To accomplish these results, I preferably provide a flat spring steel strip of thin metal 20. It resembles in plan view, Fig. 5, one common form of paper clip in that it has a generally rectangular shape with a longitudinally arranged spring finger or integral tongue piece 21 cut out of its surface by providing a U-shaped opening as shown. This tongue 21, however, is preferably made in the metal strip so as to present in side 25 view, Fig. 6, a slightly arched shape with its middle part slightly above one surface of the strip 20 and its free end slightly below the other surface of the strip. The tongue 21 is thus formed to present a spring finger and 30 when formed, the metal is set with a spring temper so that the finger or tongue will perform its desired function with its end out of the plane of the bolt strip as a whole.

This thin strip 20 is received in grooves 23 40 provided in opposite sides of the cheek pieces of the lock casing. The grooves receive the strip so that the strip lies in substantially the same plane as the outer edge of the locking lever or latch 15. In this position the spring finger 21 on the strip 20 bears against the outer edge of the latch 15 to press the long arm of the latch inwardly or to latching position. Normally the spring finger is the only part of the bolt strip 20 which contacts 45 with the latch. This is so because the latch overlies the rectangular cut in the strip 20 in which the spring finger is provided. But when it is desired to double lock the handcuff, the bolt strip 20 is pushed inwardly 50 by a projection 25 on the key 26 inserted in the hole 27 provided at the side edge of the lock casing in line with the bolt or strip 20. This causes the strip at its outer part 28 to overlie the edge of the latch 15 when the teeth 55 of the latter engage the teeth of arm 3. In this position the bolt strip 20 will rigidly stop any movement of the latch toward unlocking position. In this position of the bolt strip 20 its inner edge 29 is in position for engagement by the turning of the key 26 in

the lock casing. To unlock the cuff, the key is turned first to push the bolt strip outwardly from its double locking position and then the key is turned in the opposite direction to tip the latch lever 15 against the spring finger 21 70 and separate the interengaging teeth between the latch and intermediate arm 3 out of position. Then arm 3 may be pulled open to release a wrist and the handcuff is completely unlocked. 75

It is important to safeguard the lock against being picked. One means for this purpose which may be used, is a notch 30 at the rear side bottom edge of the latch 15 opposite its teeth, into which notch the end 80 of the spring finger will drop when the handcuff is double locked, as shown in Fig. 2. The engaged surfaces are preferably wedge shaped so that considerable force is required to slide the bolt strip 20 back, particularly 85 when the end of the spring finger is in the notch. The spring and the notch are preferably arranged as indicated in Fig. 2 so that it will purposely require about all the force that can be applied by the key to make 90 the spring ride out of the notch. When this arrangement is made, any other instrument than the key (usually a bendable wire) which cannot apply force against the end 29 of the bolt strip 20 as efficiently as the key 26, will 95 not be capable of moving the bolt. Of course while the bolt is in locking position, it is impossible to tip the latch on its pivot by applying force to the end of the latch lever even by the key. So the latch is most effectively double locked by the bolt and cooperates with the bolt to prevent lock picking operations. 100

Before the bolt is moved to double lock the handcuff, the latch lever 15 single locks 105 it by reason of the spring 21, provided the teeth are in engagement and a wrist is clasped by the arms, because arm 3 can turn in one direction until it is stopped by the wrist or its equivalent. In this position of the parts which occurs when the arresting officer fails to double lock the cuffs, it might be possible to pick the lock by slipping a thin strip like a watch spring or a wire between the intermediate arm 3 and the lock casing 110 part B, so that the strip will pry the latch teeth outwardly and prevent their engagement with the teeth on the arm 3 as the latter is carefully drawn back to release the wrist. The structure shown in Fig. 9 is particularly designed to prevent this and as an 115 extra precaution is adapted to render the single lock more effective if in practice the officer at any time fails to double lock the cuff. 120

The structure consists in the adaptation 125 of a type of escapement known in watch or clock work as a Swiss verge. Its general operation is well understood by watch makers. The lever 40 is pivoted intermediate its 130

ends and at each end is provided with a tooth 41. The teeth on the edge of arm 3 successively engage first one and then the other of teeth 41 on the lever. At each engagement of one tooth 41 the lever is caused to tip the other tooth into engagement with a tooth on the arm 3, and the first tooth is released from its engagement by the movement of the arm which causes the tipping. Thus, as arm 3 is turned past the verge or lever 40, the latter is tipped up and down and first one and then the other of its two teeth 41 is always approaching the teeth on the arm for engagement. The arm 3 cannot pass the lever 40 without causing the latter to "see-saw" as it releases successive teeth on the arm.

With this mechanism, it should be clear that any attempt to reach the latch teeth by inserting a thin flat spring or lock-picking instrument from the outside of the lock casing, will be stopped. If the picking spring is able to pass the first tooth 40 of the verge, it will prevent such tooth from engaging the teeth on the arm 3 and the second tooth 40 cannot leave its engagement with such teeth unless the first tooth can move to its engagement. Thus the picking instrument is effectively "boxed" before it can reach the teeth of latch 15 and the handcuff cannot be picked by the proposed method. The space occupied by the verge is not necessarily greater than would be desirable in any event for keeping the latch teeth engagement positioned at a distance from the place in the lock casing where the arm 3 must enter in its swinging movement. In fact the verge is a working means to block off the entrance to the casing where ordinarily an inert stationary block as part of spacer block B would otherwise be desirable. And the close fit between the arm 3 and the lock casing is not so necessary for lock picking precaution when the verge is used as when it is not used.

Of course the two cuffs shown in the drawings are preferably made exactly alike to be locked in the same way and to be unlocked with the same key. The form of key, the key hole in the lock casing, and the post are designed as shown in Figs. 1, 7, and 8, so as to safeguard the lock against the insertion of picking instruments having adequate strength to manipulate the lock mechanism.

In the consideration of this invention, it should be kept in mind that the problem is not to get an improved lock mechanism per se but to provide an improved lock related and combined with the cooperating parts of a handcuff for police use. There are adequate locks in the arts of all sorts of construction which are safeguarded against lock picking operations. But such locks are not feasible for handcuff combinations. The principal reason is that the attempted application of such prior art locks to handcuff use puts the

combination completely out of balance as to relative size, weight, and form.

An important characteristic of the preferred type of handcuff to which the detailed description is directed as an illustration of the improvements, is that arrangement of arms and locking means which permits one arm to continue a rotary movement clear around the other one and to remain unlocked until the two arms embrace a wrist or its equivalent. This broad characteristic was first disclosed in the Carney Patent No. 1,017,955 and since it issued, there have been various developments of the type including my own earlier patent, and others, known as the Wesson patents. But in all such prior developments, it has been thought necessary to provide a lock casing and lock mechanism which is in fact wholly out of proportion to the needs of the combination with the embracing arms. In this invention I disclose the means of accomplishing a highly desirable combination of embracing arms and lock mechanism in the desired type of handcuff structure without the great disproportion in size, weight, and form found in the prior art structures.

The new structure avoids the bungling size of the prior art handcuffs. It avoids the unnecessary weight. It avoids the protruding corners. It presents a handcuff for police use which more closely approaches a simple bracelet in size, weight, appearance, and facility of handling. In other words, the present structure is a long development away from the "ball and chain" idea which has been characteristic of police equipment in the past. The officer in actual practice constantly feels the need of a simpler form of equipment but one which will still function for his purpose when he needs it. The present invention supplies this need by the means herein described and their reasonable equivalents.

What I claim is:

1. A prisoner's cuff for police use including in combination a pair of curved arms pivoted together for clasping movements and locking mechanism on the normally free ends of said arms adapted to prevent unclasping movements of the arms, said locking mechanism comprising teeth on the edge of one arm, a straight latch pivoted on the other arm, provided with one or more teeth near one end to engage the teeth of the first arm, and provided with an engaging part near the other end to tip the latch for unlocking and a bolt operable to prevent the latch tipping, said bolt and latch arranged substantially parallel to each other and to a tangent of the arm to be locked and a key to operate said latch and bolt.

2. A prisoner's cuff for police use formed of curved clasping arms pivoted together, the normally free ends of which are provided

with locking means, movable parts for said locking means comprising a straight latch lever pivoted to one arm and with teeth to engage one or more teeth on the other arm, a bolt slideable in the first arm parallel to and adjacent the lever and operable into and out of position to hold said teeth in engagement, said bolt and lever being operable by a single key to disengage the teeth.

3. A prisoner's cuff for police use formed of curved clasping arms pivoted together, the normally free ends of which are provided with locking means, movable parts for said locking means comprising a straight latch lever pivoted between its ends to one arm, interengaging teeth near one end of the lever and on the other arm, a bolt to lock the lever in teeth engaging position and slideable in the arm parallel to and adjacent the lever, and means on the bolt and lever for operation by a single key to move them successively to unlocking position.

4. A prisoner's cuff for police use comprising two parallel curved arms, a spacer means extending between said arms and from one end and adjacent the outer edges of the arms over a sufficient arc toward the other end to form with the inner faces of the arms an elongated shallow lock casing, a third curved arm pivoted between the two ends of the parallel arms opposite the lock casing and adapted to turn so as to bring its normally free end into closing position along the top of the lock casing, and elongated means within said lock casing adapted to engage the end of said arm and hold it in locked position.

5. A prisoner's cuff for police use comprising a pair of parallel spaced arms and an oppositely curved arm pivoted at one end between adjacent ends of the spaced arms, the latter having at the other ends a lock casing formed between them, said lock casing being arranged as an elongated shallow trough of a depth about equal to the width of the arms, a bottom closure forming with the sides of the arms the walls of said trough, elongated lock mechanism in the trough arranged to engage and hold the end of the intermediate arm as it turns to locking position.

6. A prisoner's cuff for police use comprising two parallel spaced arms and an intermediate arm pivoted between two of the adjacent ends of the spaced arms for complete rotation, a lock casing at the opposite adjacent ends of the spaced arms formed between the sides of the arms and of a depth about equal to the width of the arms between their ends, a bottom closure for the lock casing, a straight latch arranged longitudinally of the lock casing and pivoted in the casing, said latch and intermediate arm having interengaging locking means adapted to prevent rotation of said arm in one direction and all arranged to permit complete rotation in the other direction.

7. A prisoner's cuff for police use comprising two parallel spaced arms and an intermediate arm pivoted between two of the adjacent ends of the spaced arms for complete rotation, a lock casing at the opposite adjacent ends of the spaced arms formed between the sides of the arms and of a depth about equal to the width of the arms between their ends, a bottom closure for the lock casing, said lock casing adapted to permit a complete passage of the intermediate arm, a straight latch arranged longitudinally of the lock casing and pivoted in the casing, said latch and intermediate arm having interengaging locking means adapted to prevent rotation of said arm in one direction, and a bolt operable to hold said latch in locking position.

8. A prisoner's cuff for police use comprising two parallel spaced arms and an intermediate arm pivoted between two of the adjacent ends of the spaced arms for complete rotation, a lock casing at the opposite adjacent ends of the spaced arms formed between the sides of the arms and of a depth about equal to the width of the arms between their ends, a bottom closure for the lock casing, a straight latch arranged longitudinally of the lock casing and pivoted in the casing, said latch and intermediate arm having interengaging locking means adapted to prevent rotation of said arm in one direction, and a bolt operable to hold said latch in locking position, and key operated means to throw said bolt and release said latch from engagement with the intermediate arm.

9. A prisoner's cuff for police use comprising two parallel spaced arms and an intermediate arm pivoted between two of the adjacent ends of the spaced arms for complete rotation, a lock casing at the opposite adjacent ends of the spaced arms formed between the sides of the arms and of a depth about equal to the width of the arms between their ends, a bottom closure for the lock casing, a straight latch arranged longitudinally of the lock casing and pivoted in the casing, said latch and intermediate arm having interengaging locking means adapted to prevent rotation of said arm in one direction, said lock casing adapted to permit complete rotation of said arm in the other direction, a bolt arranged to slide in the lock casing parallel to the latch and a spring carried by the bolt operable to press the latch into locking position.

10. A prisoner's cuff for police use comprising two parallel spaced arms and an intermediate arm pivoted between two of the adjacent ends of the spaced arms for complete rotation, a lock casing at the opposite adjacent ends of the spaced arms formed between the sides of the arms and of a depth about equal to the width of the arms between their ends, a bottom closure for the lock casing, a straight latch pivoted intermediate its

ends and arranged longitudinally of the lock casing, said latch having adjacent one end interengaging locking means with corresponding means on the intermediate arm and 5 having key engaging means at the opposite end to release said latch.

11. A prisoner's cuff for police use comprising two parallel spaced arms and an intermediate arm pivoted between two of the adjacent ends of the spaced arms, a lock casing at the opposite adjacent ends of the spaced arms formed between the sides of the arms and of a depth about equal to the width of the arms between their ends, a bottom closure for the lock casing, a straight latch pivoted intermediate its ends and arranged longitudinally of the lock casing, said latch having adjacent one end interengaging locking means with corresponding means on the intermediate arm and having key engaging means at the opposite end to release said latch, and a spring bolt slidable in the casing parallel to said latch having a part to hold the latch rigidly in locking position and a part to hold the latch spring pressed into locking position, said bolt being operable by the same key that operates the latch.

12. A prisoner's cuff for police use of the character described comprising a plurality of swinging arms, one of which has locking teeth on the edge thereof near its normally free end, a lock casing on another arm having locking means therein to engage said teeth and lock the arm thereof against movement, said locking means comprising a pivoted latch member and a bolt made of spring steel, said bolt having a spring tongue normally bearing on the latch to press it to locking position and also having a shoulder to jam the latch against all movement, said bolt being movable in the casing for its spring to function alone or for its shoulder to function and completely dominate the position of the latch.

13. A prisoner's cuff for police use comprising pivoted bracelet arms, locking means including teeth on the free end of one arm and a lock casing with lock mechanism therein adjacent and carried by the end of the other arm, said lock mechanism including mechanism comprising a small pivoted lever with ends adapted to be alternately engaged and the lever rocked by the passage of the said teeth on the first mentioned arm whereby the latter will have one end or the other of said lever in constant engagement with the teeth thereon to prevent lock picking operations, said lever being located in the lock casing next to the entrance for the first mentioned arm as it swings with respect to the other arm.

14. A prisoner's cuff for police use comprising bracelet arms movable to embrace the wrist, interengaging locking mechanism on said arms including a rocking lever means, means operable by the movement of the arms

and located to prevent picking operations in the space between the arms when they are in overlapped position for locking on a wrist.

15. A prisoner's cuff for police use comprising two parallel arms having a lock casing between them at one end, an intermediate arm pivoted at the other end for complete rotation, teeth on the outer edge of the intermediate arm adapted to pass across the top of the lock casing, a spring latch in the lock casing arranged to engage said teeth and prevent movement of the intermediate arm in one direction and a rocking lever means in the casing operable by said teeth to prevent the insertion of a picking instrument from without the casing and between the teeth and the spring latch.

16. A prisoner's cuff for police use of the kind described, including relatively rotatable arms, one of which carries a lock mechanism, and the other means to be engaged thereby, said lock mechanism having a latch arranged for pivotal movement and a bolt slidably mounted in close parallel relation to the latch with a cut-out portion to permit movement of the latch in one position of the bolt and a cross-portion to prevent movement of the latch in another position of the bolt, a spring bearing on the latch through said cut-out portion, one end of said latch and bolt being positioned for unlocking operations by opposite movements of a key in the lock mechanism.

17. A prisoner's cuff for police use of the kind described, including a lock casing with a pivoted latch and slidable bolt therein, operable in one direction from without the casing, said bolt having guiding engagement with grooves in the opposite sides of the casing and adapted to overlie said latch, with a cut-out portion having a spring finger on the bolt centrally of the cut-out portion to bear on the latch and a rigid shoulder to also bear on the latch, depending on the position of the bolt, said latch having a hooked portion at one end within which a key may be positioned for turning, the end of said bolt being adapted to overlie the hook portion in the path of the key when in rigid engagement with the latch.

18. A prisoner's cuff for police use formed of curved clasping arms pivoted together, one having at its outer end a lock casing, said lock casing being arranged as an elongated shallow trough of a depth about equal to the width of either arm, elongated lock mechanism including a substantially straight latch and a bolt underlying the latch both parallel to the bottom of the lock casing in the trough on one arm arranged to engage and hold the outer end of the other arm as it turns to locking position, said last named arm forming a top closing wall for the trough-shaped casing when the arms are in locked position.

19. A prisoner's cuff for police use com-

prising pivoted bracelet arms, locking means on the free end of one arm and a lock casing with lock mechanism therein adjacent and carried by the end of the other arm, said lock mechanism including a lever pivoted within the lock casing and having toothed ends alternately engageable by said locking means to rock the lever and adapted to entrap the end of a lock-picking blade forced between the lock casing and the said free end.

20. A handcuff comprising a pair of curved clasping arms with two ends pivoted together for complete relative rotation, the free ends of the arms being formed so as to overlap for locking engagement, an elongated shallow lock chamber carried by one of the arms and of a substantially uniform depth along a radius from the pivot, said depth being about equal to the width of the 25 arms, teeth on the other arm, and locking means located wholly within the lock chamber and including a substantially straight latch and a bolt underlying the latch both parallel to the bottom of the lock casing engageable with the teeth to lock the arms together.

In testimony whereof I have affixed my signature.

ELMER E. NEAL.
